(57) **CLAIM**

I claim the ornamental design for the baseball rebounder, as shown and described.

DESCRIPTION

FIG. 1 is a front elevational view of a baseball rebounder showing my new design;

FIG. 2 is a top view thereof;

FIG. 3 is a bottom view thereof;

FIG. 4 is a left side view thereof; the right side view is the mirror image of FIG. 4;

FIG. 5 is a rear view thereof; and,

FIG. 6 is a perspective view thereof.
